UNITED STATES PATENT OFFICE.

WILLIAM F. DRAPER, OF HOPEDALE, MASSACHUSETTS.

SUPPORT FOR SPINNING-SPINDLES.

SPECIFICATION forming part of Letters Patent No. 392,912, dated November 13, 1888.

Application filed May 1, 1888. Serial No. 272,517. (No model.)

To all whom it may concern:

Be it known that I, WILLIAM F. DRAPER, of Hopedale, county of Worcester, State of Massachusetts, have invented an Improvement in Supports for Spinning-Spindles, of which the following description, in connection with the accompanying drawings, is a specification, like letters on the drawings representing like parts.

10 This invention has for its object to provide a spindle with bearings wherein it may run with the minimum of friction and with great steadiness or freedom from gyration.

In accordance with my invention I have 15 provided the supporting-case or holder within the sleeve-whirl with a lateral bearing having rolling surfaces, and the step I have supported loosely or by means of a spring.

My invention consists, essentially, in a spindle and supporting-case or holder combined 20 with a bolster or bearing having rolling surfaces and with a step and a spring to sustain it in a yielding manner, as will be hereinafter described.

25 Figure 1 in section shows a rail, a spindle-supporting case or holder, and bolster and step bearings embodying my invention, and a sleeve-whirl, the spindle being shown in elevation. Fig. 2 is a section of Fig. 1 in the line 30 *x*, and Fig. 3 shows the spider for holding the rolling surfaces of the bolster-bearing.

The rail A, the spindle-supporting case or holder B, and the spindle C, having the sleeve-whirl C', are and may be all as usual. The 35 case or holder is kept seated on the rail B by a suitable nut, D, which, as herein shown, is extended and made as a cup to receive loosely the step E, the shank of which is shown as surrounded by a spring, e', which latter sustains the step in a yielding manner and permits it to move laterally with the lower end of

the spindle to thus avoid jar, as is well understood.

At or near its upper end, and at a point within the sleeve-whirl, I have provided the 45 case or holder with a bolster having rolling surfaces b b, kept within the case in proper position by, as herein shown, a spider, e, the lower ends of the rolling or cylindrical surfaces being supported by and rotating on a 50 bearing-plate, b², sustained by a shoulder in the case B.

I do not herein claim a bearing having rolling and rigid surfaces, as the same has been made the subject of claim in my application, 55 Serial No. 266,730, filed March 9, 1888.

I have herein shown the spring e' of such construction as to permit not only lateral motion of the foot of the spindle, but also a slight extent of vertical motion; but I desire 6c it to be understood that I should consider as within my invention any form of spring which permitted only a lateral motion to the step.

I claim—

1. The spindle and the supporting-case or 65 holder, combined with a bolster-bearing having rolling surfaces and with a step and spring to support and permit the step to move laterally, substantially as described.

2. The spindle and the supporting-case or 70 holder, combined with the bolster-bearing having rolling surfaces b, and a step and spring to support and permit the step to yield not only laterally, but vertically, substantially as described.

In testimony whereof I have signed my name to this specification in the presence of two subscribing witnesses.

WM. F. DRAPER.
